UNITED STATES PATENT OFFICE

CHARLES WEISS, OF NEW YORK, N. Y.

DESIGN FOR A PLATE OR THE LIKE

Application filed June 27, 1929. Serial No. 31,849. Term of patent 14 years.

To all whom it may concern:

Be it known that I, CHARLES WEISS, a citizen of the United States, and resident of the borough of Manhattan, city, county, and State of New York, have invented a new, original, and ornamental Design for a Plate or the Like, of which the following is a specification, reference being had to the accompanying drawing, forming part hereof, in which—

Fig. 1 is a top plan view and Fig. 2 is a central sectional view of a plate or the like illustrating my new design.

I claim:

The ornamental design for a plate or the like, as shown.

CHARLES WEISS.
